DISPLAY DEVICE

Charles A. Long, Jr., Haddon Heights, N. J.

Application December 1, 1936, Serial No. 113,560

6 Claims. (Cl. 211—135)

My invention relates to a new and useful display device and it relates more particularly to a display device of the knock-down variety which can be shipped in quantities in a flat condition 5 to be erected or set up at the place of use.

My invention further relates to a display device which lends itself equally to a counter or shelf display as well as to window or outside displays and one which, while made of ordinary 10 card-board and of an extremely simple construction, is nevertheless so designed as to be capable of supporting relatively great weight.

My invention still further relates to a display of this character which, in addition to the foregoing features, also is of a very attractive appearance and affords ample room for advertising matter relating to the object displayed.

In the accompanying drawings:

Fig. 1 represents a front elevation of a display 20 device embodying my invention shown set up and ready for use.

Fig. 2 represents a bottom plan view of Fig. 1.

Fig. 3 represents a section on line 3—3 of Fig. 1.

Fig. 4 represents an end elevation of Fig. 1 25 showing the device in a collapsed or knock-down position.

Fig. 5 represents a fragmentary rear elevation of the lower portion of Fig. 1 showing details of construction.

Fig. 6 represents, on an enlarged scale, a section on line 6—6 of Fig. 5.

Fig. 7 represents, on an enlarged scale, a section on line 7—7 of Fig. 1.

Figs. 8, 9, 10 and 11 represent views similar to 30 Figs. 1, 2, 3 and 4 respectively showing a modified form of construction.

Referring to the drawings in which like reference characters represent like parts, I designate a vertical body portion which is provided with any desired artistic contour 2 and on the front face of which any desired advertising matter (not shown) may be inscribed. To the back of the body portion 1 is adhesively secured a hinged easel 3 which may lie flat 45 against the body portion 1 as shown in Fig. 4 or which may be extended at an angle thereto to form a support as shown in Fig. 3. Associated with the body portion 1 is a platform construction comprising the lower end platforms 5 and 6 50 and the intermediate elevated platform 7 on which electric storage batteries 8 or other devices to be displayed are positioned. The platforms 5, 6 and 7 are formed from an initially integral blank comprising the back wall 9, the top wall 10 and the front wall 11, the top wall 10 being

increased longitudinally to permit collapse of the platforms against the body portion 1, as best seen in Fig. 4. In order to form the end platforms 5 and 6 lower than the intermediate platform 7, the tops 10 of the end platforms 5 and 6 are cut off at their junction with the back wall 9, shortened and are then secured thereto as at 12 (see Fig. 7) it being understood that the top 10 of the intermediate platform 7 is integral with the back wall 9, as best seen in Fig. 3. In order to secure the bottom platform construction to the body portion 1 the back wall 9 is provided with the inner tabs 13 which are secured to the back wall 9 as at 14, and to which are pivoted at 15 the outer tabs 16. The tabs 13 and 16 are adapted to engage corresponding cut-outs 17 in the lower portion of the body portion 1 in which position the pivoted tabs are turned upon their pivot to form a lock as best shown in Fig. 5. In order to reinforce the construction and to enable it to support the relatively heavy weight of electric storage batteries or the like, I provide the legs 18 which are suitably secured to the front and back walls 9 and 11 of the platform construction and which are centrally scored to permit them to collapse as shown in Fig. 4, it being understood that the end legs collapse in the direction of the arrow 21 (Fig. 2), while the intermediate legs collapse in the opposite directions of the arrows 22. When the device is shipped, it is in the knock-down 25 position with the tabs 13 and 16 in registration with and engaging the cut-outs 17 in the locking position shown in Figs. 5 and 6. In order to erect the device it is merely necessary to exert downward pressure on any one of the platforms 5, 6 and 7 which will automatically spread all three platforms from the folded or collapsed position shown in Fig. 4 to the operative position shown in Fig. 3. The tops 10 of the platforms 5, 6 and 7 are provided with the tabs 23 which are cut-out therefrom as at 24, said tabs serving to carry specific information relating to the particular object on the particular platform and further enhancing the attractiveness of the device.

In Figs. 8 to 11 I have shown a modified form of 45 construction in which I have the end platforms 5 and 6 and the central elevated platforms 7, except that in addition thereto I have a fourth platform 26 which is below and projects into a plane beyond the vertical plane of the front wall 50 of the central platform 7. The additional platform 26, as will be best seen from Figs. 9, 10 and 11, is formed from a continuation or extension of the front wall 11 of the middle platform 7 which extends horizontally to form the top wall 10x and 55

the front wall 11x of the additional platform 26. In order to accomplish this the end platforms 5 and 6 instead of being integral with the central platform 7, as in Figs. 1 to 7, are, in this modified form, severed therefrom as at 27, and the legs 18 supporting the central platform 7 are extended to reach all the way to the floor or other support. A pair of legs 18x, similar in construction to the legs 18, are provided to support the additional platform 26. The legs 18 and 18x, shown in Fig. 9, are identical except that the legs 18 supporting the central platform are located more centrally of said platform 26 instead of near the edges thereof as shown in Fig. 2.

15 Having thus described my invention what I claim as new and desire to secure by Letters Patent is:

1. A display device comprising a vertical body portion, a separable platform construction for supporting the object to be displayed secured to the lower front portion of said vertical body portion, said separable platform construction comprising a plurality of platforms in different horizontal and vertical planes, and means for 25 detachably locking said platform construction to said vertical body portion.

2. A display device comprising a vertical body portion and a collapsible platform construction secured to the lower front portion of said vertical body portion, said platform construction comprising a plurality of platforms in different vertical and horizontal planes.

3. A display device comprising a substantially upright member and a substantially horizontal 35 platform construction, said platform construc-

tion comprising a plurality of platform constructions, each of said platform constructions being formed of an integral blank forming a relatively high platform, the upper portion of the wall of said platform construction being severed from the rest of the blank and shortened to form a plurality of relatively low platforms. 5

4. A display device comprising a collapsible platform construction, said platform construction comprising a plurality of platform constructions, 10 each of said platform constructions being formed of an integral blank forming a collapsible relatively high platform, the upper portion of the wall of said platform construction being severed from the rest of the blank and shortened to form a 15 plurality of relatively low collapsible platforms.

5. A display device comprising an upright member, a plurality of separate platform constructions each formed of an integral piece comprising a horizontal top and vertical rear and front walls 20 and secured at its rear wall to one side of said upright member, one of said platforms having the front wall thereof extended to form a second platform in different vertical and horizontal planes therefrom, and collapsible legs secured to 25 the front and rear walls of said platform constructions for supporting said platforms.

6. A display device comprising an upright member, a plurality of platforms on different planes secured to a face of said upright member, one of 30 said platforms having a wall thereof extended to form an auxiliary platform in vertical and horizontal planes different from the planes of said first mentioned platforms.
